UNITED STATES PATENT OFFICE.

CHARLES F. HENNING, OF CHICAGO, ILLINOIS, ASSIGNOR TO THE UNITED STATES GYPSUM COMPANY, OF CHICAGO, ILLINOIS, A CORPORATION OF NEW JERSEY.

CORE FOR REINFORCED CONCRETE OR PLASTER FLOOR CONSTRUCTION.

1,218,999.

Specification of Letters Patent. Patented Mar. 13, 1917.

Original application filed April 9, 1915, Serial No. 20,162. Divided and this application filed July 28, 1915. Serial No. 41,887.

To all whom it may concern:

Be it known that I, CHARLES F. HENNING, a citizen of the United States, residing at Chicago, in the county of Cook and State of Illinois, have invented certain new and useful Improvements in Cores for Reinforced Concrete or Plaster Floor Construction, of which the following is a specification.

My invention relates in general to floor construction and more specifically to a void-forming core adapted to materially diminish the weight of concrete and plaster floors without affecting the strength of the floor. The present application is a division of my pending application Serial No. 20,162, filed April 9, 1915.

In order to meet the requirements of a thoroughly satisfactory void-producing core for use in floor construction the core must be light in weight, strong and substantial, capable of being manufactured in relatively large sizes, uniform in size and shape, capable of being easily fitted into position, fire and water-proof and non-conductive of sound.

It is the object of my invention to produce a core which meets all of the above requirements and which is in every way superior to the devices heretofore in use for this purpose in the art.

Another further object of my invention is to produce concrete floors of much lighter construction than has heretofore been possible, a great saving in material being effected by the comparatively light weight of the cores employed.

Further objects and advantages of my invention will be apparent as it is better understood by reference to the following specification when read in connection with the accompanying drawing in which—

Figure 1 is a perspective view of a complete core ready to be placed in position;

Fig. 2 is a vertical section of a floor showing the cores disposed side by side and the manner of applying the ceiling plaster; and

Fig. 3 is a vertical section through a sheet of plaster board of the type which I preferably employ in carrying out my invention.

Referring to the drawings, 1 indicates generally a core of plaster board provided with a top 2 and sides 3, having flanges 4 forming supporting feet for the core and adapted to space the cores laterally when

placed side by side as indicated in Fig. 2. 55 The bottom 5, consisting of a single sheet of plaster board is secured to the flanges 4 by means of clips 6 of which any suitable number may be employed. The clips are preferably of soft iron, easily bent in any desired 60 direction and are provided with upwardly extending tongues 7 adapted to be embedded in the concrete as indicated in Fig. 2.

The method of making the cores is as follows: The plaster-of-Paris, mixed with 65 water to the proper consistency and containing, if desired, a certain proportion of pulverized hardened plaster which acts as an accelerator for the setting operation, is disposed between opposite sheets of a reinforcing material, preferably a wool felt, and the mass is subjected to pressure whereby the plaster is forced into the interstices of the felt and becomes incorporated therewith to form a strong bond between the felt and 70 plaster. The result is a sheet of plaster board which, while the plaster is still in a plastic condition is molded in any suitable manner to the form indicated in Fig. 1. The plaster is then allowed to set and the molded 75 core is dried after which it is dipped in or otherwise coated with a suitable waterproofing material, such as pitch. The waterproofing material impregnates the surfaces of the molded core and not only waterproofs the structure but strengthens it to a considerable extent so that it is better able to withstand rough usage in shipment and the handling necessary during building operations. The molded portion of the core 80 is assembled with the bottom sheets 5 and secured thereto by clips 6 at the job. The bottom sheets 5 may be water-proofed if desired.

I have described my method in its simplest form and in connection with a plaster board consisting of a layer of plaster covered on either side by a sheet of reinforcing material. If desired the plaster board may be made as in Fig. 3 and consisting of a 85 plurality of layers of plaster 16 and reinforcing material 17. The resulting plaster board is molded to form the cores exactly as in the preceding description.

Preferably the pressure to which the mass 90 is subjected to force the plaster and reinforcing material together is exerted by suitable rolls so that the method may be

continuous. In carrying out the method the cores may be molded in a continuous sheet of plaster board and separated after the plaster is hardened or, if desired, the 5 plaster board may be cut into desired lengths while the plaster is still in the plastic condition and subsequently molded before the plaster hardens. In either case the water-proofing step will follow the drying 10 operation after which the cores, which are cut to uniform and standard sizes, are ready for shipment.

In the use of my invention a suitable false-work is erected which need comprise 15 only beams, spaced at intervals equal to the width of the cores and the cores with their bottoms secured in place by means of the clips 6 are mounted in rows on the beams, end to end, and with the flanges 4 of adjacent 20 rows engaging, as indicated in Fig. 2. Preferably the individual cores of adjacent rows are disposed in staggered relation so that the joints between the cores in the adjacent rows are not in the same line. When 25 all of the cores are in place the reinforcing members 8 are placed in position and the concrete 9 is poured and allowed to harden. The concrete enters the spaces between the adjacent rows of cores and forms beam sections 30 which, with the reinforcing members, support the load of the floor. The ceiling plaster 10 is applied directly to the bottom sheets 5 of the cores and owing to the nature of the reinforcing material the ceiling 35 plaster forms a strong bond with the sheets 5 which hold the plaster in position indefinitely.

Plaster board is comparatively light in weight and a saving of approximately 40 twenty-five pounds per square foot in the weight of the cores alone is possible where plaster board cores are substituted for the clay tile of the prior art. A further saving is effected in the amount of concrete and 45 steel necessary to sustain the dead-load of the floor and both of these savings are transferred in turn to the supporting columns which may be correspondingly lighter. Cores of plaster board are also lighter than 50 the cores of solid plaster, concrete or sheet metal of the prior art.

Cores of plaster board are strong and substantial, withstanding rough usage in shipment and setting, and are preferable to 55 clay tile cores which are exceedingly brittle and sheet metal cores which are easily dented and deformed when repeatedly handled by careless workmen. Solid plaster cores are too fragile for commercial use 60 and cement cores are obviously too heavy for economical shipment.

Plaster board cores may be made in relatively large sizes of uniform shape and size, whereas clay tile cores are limited in size 65 owing to difficulty of firing. Clay tile cores

are, even in the smaller sizes, always more or less warped and are, therefore, not uniform in shape. Sheet metal cores are so deformed by handling that they are rarely of uniform shape when they reach the job. By the use of plaster board cores longer 70 spans are possible and a larger amount of space is thereby possible in a building of given size. The uniform shape of plaster board cores allows them to be more readily placed in position and inasmuch as the plaster board may be neatly cut and trimmed by means of ordinary carpenter's tools a considerable saving in labor is effected by the use of these cores rather than those of the prior art which are cut with difficulty 75 and are frequently spoiled during the cutting operation.

Plaster board is extremely resistant to fire and it will be readily understood from the foregoing description and by reference to the drawing, particularly Fig. 2, that by the use of my invention the under-side of the concrete is protected from fire by two layers of plaster board and in addition a large part 80 of the under surface is further protected by the dead air space within the cores. Furthermore should all or portions of the ceiling plaster be damaged, by fire for example, and the bottom sheets 5 thereunder be injured, the ceiling may be easily replaced or repaired by bending the clips and removing and replacing the injured sheets with new sheets after which ceiling plaster can be applied to the new sheets as before. This can 85 be done without injury to the cores or floor structure and without necessitating the replacement of any other parts than the bottom sheets, thereby greatly reducing the cost of replacing or repairing the ceiling. 90

By the use of cores having plaster board bottoms to which the ceiling plaster may be directly applied a material saving in the cost of plastering is effected. Wire lath has been universally used with metal domes as a 100 base to which the ceiling plaster is applied. This material invariably sags and a greater thickness of plaster grounds is required not only to securely bond the plaster to the wire lath but also to obtain a flat ceiling, it being 105 obvious that the distance of the wire lath surface from the lower surface of the floor is greater at the center of the span than at its ends owing to the sag of the wire lath. When clay tile are used the ceiling surface is 110 uneven and irregular and an excessive amount of plaster must be used to obtain uniform grounds. Plaster board not only bonds with the ceiling plaster without the necessity of providing openings into which 115 the plaster is forced as in wire lath and clay tile practice but also provides a flat surface throughout the span so that the thickness of the plaster grounds does not vary. The ceiling plaster is much more readily applied to 120 125 130

plaster board than to wire lath since the plaster board presents a firm surface to the plasterer, whereas the wire lath moves up and down at each application of the plasterer's tools.

5 The continuous ceiling surface eliminates the alternate light and dark lines caused by the depositing of dust in the air currents which pass through the clay tile and not 10 through the denser concrete. Also rust stains from the metal lath are eliminated. Clay tile contains oxids, salts, etc., which work out to the surface of the plaster causing efflorescence and stains.

15 It is obvious that various changes may be made in the form, construction and arrangement of the parts without departing from the spirit and scope of the invention or sacrificing any of its material advantages, the 20 form hereinbefore described being merely preferred embodiments thereof.

I claim:

1. A core for concrete and plaster con-

struction comprising an integral member 25 molded from a single sheet of plaster board and having a top, sides and outwardly projecting flanges along the lower edges of the sides, a bottom consisting of a flat sheet of plaster board, and metallic clips securing said bottom to said flanges.

2. A core for concrete and plaster floor construction comprising a member molded from a single sheet of plaster board and 30 having a top and outwardly flaring integral sides of a width equivalent to the desired depth of said core, the lower edges of said sides projecting outwardly parallel to said top and forming flanges, a bottom consisting of a flat sheet of plaster board, and metal clips securing said bottom to said 35 flanges.

CHARLES F. HENNING.
